UNITED STATES PATENT OFFICE.

JAMES KERR, OF LONDON, ENGLAND.

WOOD PAVEMENT.

SPECIFICATION forming part of Letters Patent No. 296,581, dated April 8, 1884.

Application filed December 18, 1883. (No model.) Patented in England February 15, 1877, No. 627; in France November 30, 1881, No. 146,143; in Belgium December 12, 1882, No. 59,839, and in Italy July 16, 1883.

To all whom it may concern:

Be it known that I, JAMES KERR, a subject of the Queen of Great Britain, residing at London, England, gun-manufacturer, patentee of the well-known system of wood paving, have invented new and useful Improvements in the Construction of Wood Pavements, (for which I have obtained patents in Great Britain, No. 627, bearing date February 15, 1877; in France, No. 146,143, bearing date November 30, 1881; in Belgium, No. 59,839, bearing date December 12, 1882, and in Italy, bearing date July 16, 1883,) of which the following is a specification, reference being had to the accompanying drawings.

The present invention relates to that class of wooden pavements in which wooden blocks are supported upon a concrete foundation, and has for its object to provide a novel manner of laying the wooden paving-blocks, whereby the upper portion of the latter can move or yield slightly, to satisfy the requirements of expansion and contraction, and the natural expansion of the blocks is expedited and exhausted. Furthermore, the paving-blocks are firmly united or cemented together at the base and supported upon the concrete foundation in such a manner that the pavement is prevented from bulging upward and forcing the curbstones out of place—a result liable to happen in pavements laid according to other methods.

The invention will first be fully described, and then set forth in the claims.

In the drawings, Figure 1 is a transverse section of a street-pavement laid according to my invention. Fig. 2 is a portion of the same drawn to an enlarged scale.

The wooden paving-blocks A are laid directly on a bed of concrete or ballast, B, about three-eighths of an inch apart, and a specially-prepared bitumen or bituminous composition, C, is run into the joints or interstices between the blocks to a depth of about one inch. This bituminous composition flows around the blocks and forms, as it were, a shoe or clamp around each individual block, thereby fixing the blocks in position at once, and holding them so firmly that they cannot be moved without breaking them to pieces. It should be stated, however, that the upper portion of the blocks can move or yield slightly, to allow

for the proper expansion and contraction thereof, and for this reason the work of laying the blocks can be carried on or continued without hindrance, as the operation of filling up the remaining portion of the interstices between the blocks can be proceeded with at once and allowed to consolidate thoroughly by reason of the solid manner in which the blocks are held at their base. The space left between the blocks above the bottom cementing or uniting composition or bitumen is of considerable depth, and is entirely filled up with a liquid grouting, D. The latter has the effect of expediting and exhausting the natural expansion of the blocks, so that when once laid upon the principle above set forth the pavement is prevented from bulging upward and forcing the curbs out of position, as is liable to occur in pavements laid in the ordinary way.

It has heretofore been stated that the paving-blocks are laid directly upon a foundation or bed of concrete, whereas in ordinary pavements embracing the use of a concrete foundation the blocks are set into a top stratum of asphalt. By laying the blocks in the manner proposed by me—that is, running in between the blocks a very slight depth of bitumen or any of its compounds—I hermetically seal up the interstices or joints between the blocks, in addition to firmly or solidly uniting the latter, and for this reason I effectually prevent the percolation of water through the pavement. The bituminous or asphalt filling, however, is sufficiently elastic and yielding to allow for any slight expansion which the blocks may have. It may be stated that in practice the blocks are impregnated with creosote-oil specially distilled from coal-tar. This mode of preparing the blocks renders them nearly permanently proof against water or moisture, and affords, to a great extent, the means of preventing the expansion and contraction of the blocks, and the consequent injury to the pavement.

The bitumen or composition for uniting the paving-blocks at the base and forming the so-called "clamping-shoes" around the same generally consists of the following ingredients, viz: best British pitch, green or heavy oil, and whiting-powder, in the following proportions, viz: five parts, by weight, of the pitch; one part, by weight of the oil, and one part,

by weight, of the whiting-powder. The upper portion of the interstices between the blocks is filled up with lime or cement grouting, which in its liquid state will, to a great extent, exhaust all of the expansion that can take place in the blocks while the work is proceeding, thereby preventing the disturbing of the pavement from expansion when finished. The grouting will also be compressible in the event of any expansion of the wood blocks. By these precautions I effectually provide for the prevention of such a disturbance of the blocks as would force the curbstones out of place or bulge up the pavement.

15 Having thus described my invention, what I claim is—

1. The art of laying wooden pavements consisting in setting wooden blocks directly upon a solid concrete foundation or bed, running liquid asphalt or bitumen into the interstices

or joints between the blocks for partly filling said interstices or joints, and then completely filling the latter by a cement grouting, as and for the purpose set forth.

2. A pavement consisting of a concrete 25 foundation or bed, wooden blocks placed directly thereon, asphalt or bitumen clamping-shoes uniting the blocks at their bases, and a cement grouting filling the spaces between the blocks above said asphalt clamping-shoe, substantially as described.

In testimony whereof I have hereunto signed my name in the presence of two subscribing witnesses.

JAMES KERR.
